UNITED STATES PATENT OFFICE

AUGUST H. LOF, OF BROOKLYN, NEW YORK

AWNNG FIXTURE

Application filed August 4, 1930. Serial No. 472,790.

This invention relates to improvements in awning fixtures, the principal object of the invention being to provide an improved device of this character by means of which the awning rods are automatically locked in position and which fixture is extremely simple in construction and efficient in operation.

Other objects and advantages of the invention will appear as the description proceeds.

10 In the drawings accompanying this specification,

Fig. 1 is a perspective view showing an awning supported in open position in front of a window by means of the improved fixtures;

Fig. 2 is a front view of the upper fixture illustrating the manner in which it engages and locks the awning rod, the latter being shown broken away;

20 Fig. 3 is a perspective view of the fixture and portion of the rod shown in Fig. 2;

Fig. 4 is a front view of the lower awning fixture, the rod-receiving socket being turned upward in order to show the parts more clearly;

Fig. 5 is also a front view of the lower fixture with the rod-attaching socket removed therefrom and showing the locking lug in its releasing position;

30 Fig. 6 is a side view of the lower fixture with its locking lug in locking position; and

Fig. 7 is a transverse section taken on the line VII—VII of Fig. 6.

The same characters of reference designate 35 the same parts in the different figures of the drawings.

Referring to the drawings, and especially to Figs. 1 to 3, the upper fixture comprises a base plate 1 provided with perforations 2 and 3 for the reception of screws by which it may be secured to a window frame as shown in Fig. 1. Secured to the base plate and projecting at right angles therefrom is a member 4, the outer portion of which is curved 45 over to conform to the curvature of a rod 5 such as is commonly used for supporting awnings. The member 4 is cut away at its central portion to form a rectangular opening for the reception of a slidable locking member 53 which will now be described. The locking

member comprises a base portion 6 in contact with and slidable on the base plate 1 through the rectangular opening in the member 4. At its upper end the said base portion 6 is bent at right angles to form a side wall 7, which in turn is bent at an acute angle to form a wall 8 inclined toward the portion 6, said wall 7 being bent at an obtuse angle to form a side wall 9 parallel with the wall 7, the walls 6, 7, 8 and 9 thus forming a box-shaped member 60 disposed within the rectangular opening of the member 4, one wall of which box-shaped member is inclined to its base. The width of said box-shaped member is slightly less than the length of the opening thereby to 65 permit easy movement of the member upward in said opening. The walls 7 and 9 are provided with ears 7^a and 9^a respectively extending beyond the opposite ends of the opening in the member 4, so that after the parts of 70 the fixture have been assembled they cannot be separated. As will be seen in Figs. 2 and 3, the box-shaped member covers only the upper half of the base portion 6. Consequently, for permitting the insertion of an awning 75 rod 5 into the fixture, the plate 6 is pushed upward as far as it will go, that is, until the ears 9^a contact with the member 4. The unboxed portion of the plate 6 will then be

opposite the curved portion of the member 4 so 80 that there is plenty of room for the rod to be inserted. After insertion the rod is held in place within the curved portion of the member 4 and the plate 6 allowed to drop or is pulled downward through the opening in said 85 member 4 to the position shown in Figs. 2 and 3, in which position the inclined wall 8 acts as a wedge to clamp the rod within the curved portion of member 4 and securely hold it therein until released by manually forcing 90 the plate 6 upward. The plate 6 is cut out at its lower end, centrally thereof and bent into the form of curved ears 10, which may be used as suspension points for the usual 95 pulleys through which the awning cords pass.

The lower fixture shown in Figs. 4 to 7 comprises base portions 11 merging into a pair of outstanding ears 12 and 13 spaced apart from each other, said base portions 100 having screw-receiving openings 11^a. Se-

- cured in the ear 12 is a stud 14 extending toward the ear 13, the length of the stud being such as to reach about half-way between the ears 12 and 13. Mounted for sliding movement on the ear 13 is a locking lug 15, said lug being guided in its sliding movements by a strap 15^a mounted in a groove formed in the outer side of the ear 13, said strap being in fact an integral part of the lug but separated therefrom except at its ends by a slot of sufficient width to receive the interposed portion of the ear 13 and permit easy sliding of the lug thereon. The lug 15 is provided in its lower portion with a circular depression 16 whereby, when the lug is pushed upward on the ear 13, a space is formed between the end of the stud 14 and the lug 15, the width of said space being at least equal to the length of the stud.
- 20 In operation, the fixture is secured by its base to the lower portion of a window frame as indicated in Fig. 1. When the awning is to be put up, the lug 15 is pushed upward on the ear 13 to the position shown in Fig. 5, 25 thus forming sufficient space between the end of the stud 14 and the lug to receive the flat perforated ear 17 formed on the end of the sockets 18 which are usually screwed on the ends of the rod forming the awning frame.
- 30 As soon as the ear 17 has been pushed in until its opening or eye is in alignment with the stud 14 the ear 17 is given a slight lateral push, whereupon the stud 14 will enter the said opening thereby pivotally supporting 35 the awning frame, as shown in Fig. 4. The lug 15 is then permitted to slide downward, thereby bringing the thicker portion of the lug into such position as to fill the space between the end of the stud and the ear 13, as 40 also shown in Fig. 4. With the lug in this position it will be obvious that the awning frame cannot be removed from the fixture.
- From the foregoing it will be noted that each fixture comprises two inseparable members 45 slideable relatively to each other, one of said members serving in one position to retain the awning rod in position and in the other position to release said rod so that it can be removed from the fixture.
- 50 Having thus described my invention, what I claim is:
1. An awning fixture, comprising a bracket, means carried by said bracket for supporting an awning rod, and a member slideable between said rod-supporting means and a portion of said bracket thereby to prevent separation of the awning rod from its supporting means.
- 60 2. An awning fixture, comprising a pair of members inseparably connected together, one of said members carrying means for supporting an awning rod, and the other of said members being slideable between said supporting means and its carrying member and adapted 65 to exert a wedging effect on said rod.

3. An awning fixture, comprising a bracket, rod-supporting means carried by said bracket and spaced therefrom to permit free insertion of an awning rod in said supporting means and a member mounted for sliding movement between said bracket and the rod-supporting means thereby to lock the rod in position. 70

4. An awning fixture, comprising a bracket, rod-supporting means carried by said bracket and spaced therefrom to permit free insertion of an awning rod in said supporting means and a member mounted for sliding movement between said bracket and the rod-supporting means thereby to lock the rod in position, said slideable member and bracket being inseparably connected together. 75

5. An awning fixture, comprising a bracket, rod-supporting means carried by said bracket and spaced therefrom to permit free insertion of an awning rod in said supporting means, and a member inseparably connected with said bracket and mounted for sliding movement between the bracket and the rod-supporting means, said member being of wedged formation. 80

In testimony whereof I have signed my name to this specification.
